UNITED STATES PATENT OFFICE.

GEORGE R. MCALLASTER, OF ROCHESTER, NEW YORK.

BED.

Application filed July 27, 1918. Serial No. 247,058.

To all whom it may concern:

Be it known that I, GEORGE R. MCALLASTER, a citizen of the United States, and resident of Rochester, in the county of Monroe and State of New York, have invented certain new and useful Improvements in Beds, of which the following is a specification.

The present invention relates to beds and this application contains matter divided 10 from an application filed by me on April 5, 1918, Serial No. 226,949. An object of the invention is to provide in connection with a folding bed a screen which is mounted upon the bed frame and which, when the 15 bed is in folded condition, will effectively enclose the bed so that its character will not be recognized, while, when the bed is in position for use, will be compactly folded so as not to interfere with the use of the 20 bed.

To these and other ends the invention consists of certain parts and combinations of parts all of which will be hereinafter described, the novel features being pointed 25 out in the appended claims.

In the drawings:

Fig. 1 shows the bed in folded condition;

Fig. 2 is a section on a smaller scale on the line 2—2, Fig. 1, with the bed in folded 30 condition;

Fig. 3 is a similar section showing the bed in position for use;

Fig. 4 is a fragmentary side view of the bed in position for use;

Fig. 5 is a side elevation of the bed when 35 in condition for use;

Fig. 6 is a horizontal sectional view of another embodiment of the bed in folded condition;

Fig. 7 is a fragmentary sectional view of 40 the embodiment shown in Fig. 6, showing the bed in position for use;

Fig. 8 is a front view of the embodiment shown in Figs. 6 and 7, in folded condition;

Fig. 9 is a view in elevation of another 45 embodiment of the bed in folded condition; and Fig. 10 shows in detail one pair of hinges connecting two cooperating screen members.

In the illustrated embodiments of the invention, the bed frame is supported upon a standard which, in this instance, comprises a base frame consisting of two angle iron pieces 1 arranged in parallel relation and connected by a cross piece 2. Rising from 50 the bed frame are two uprights 3 suitably connected together and having the angle

iron side pieces 4 of the bed frame pivoted thereto at 5, the upper ends of the uprights 3 being enlarged so that the pivots 5 are to one side of the vertical longitudinal axes of 60 the uprights whereby, when the bed frame is thrown upwardly its lower end may swing beneath the pivots 5, so that the upper end of the bed frame will lie beyond the vertical axes of the uprights in order that the bed 65 frame will be supported in an upright position without any danger of accidentally returning to its lowermost position.

The side frames of the bed frame are connected at their ends most remote from the 70 standard by a cross piece 6 in the form of an angle iron, while the ends of the side pieces nearer the standard are connected by a spacing cross piece 7 on which an angle iron 8 is secured. A wire fabric 9 connects the 75 angle pieces 6 and 8 and serves to support the mattress 10. This arrangement causes the mattress to lie at the slight angle to the side pieces 4 of the bed frame and, in order that the mattress may lie horizontally when the bed is in position for use, there are provided foldable supporting legs 11 of such lengths that the side bars or pieces 4 of the bed frame, when the bed is in its lowermost position, will lie at a slight angle to the horizontal. The construction of the legs is the 80 same as that described in my aforesaid application #226,949 and will not be herein described.

To support the mattress upon the bed 90 frame when the latter is swung to an upright position, cables 12 are provided which extend along the longitudinal sides of the mattress and connect at one end to a cross bar 13 which lies in engagement with one end of 95 the mattress. The other ends of the cables are secured to eyes 14 at the swinging end of the bed frame. Between their ends the cables may be passed through eyes or loops 15 on the sides of the mattress. When the 100 mattress is secured in the manner set forth it will be sustained in cooperative relation with the fabric 9 upon the rising of the bed to an upright position, and at the same time the sides of the mattress are free from 105 the bed frame in order to permit the bed clothes to be inserted between the mattress and the wire fabric.

Any suitable means may be employed for screening the under side of the bed frame 110 when the latter is in an upright position. In the embodiment shown in Figs. 1 to 5,

two screen sections 17 are employed, in this instance, connected to the sides 4 of the bed frame by hinges 18 and 19. These hinges are so formed that the axes about 5 which the screen sections 17 turn are at slight angles to the side bars 4 of the bed frame, in order that, when the bed frame is thrown to an upright position and lies at a slight angle to the vertical axes about 10 which the screen members 17 turn, the axes will be substantially vertical. The swinging edges of the screen sections 17 are adapted to be swung in juxtaposition, as shown in Fig. 2, in order to cover the bottom of 15 the bed frame when the bed frame is upright, and in this position their lower ends cover and hide the upper portions of the uprights of the support or standard. The space between the screen members and the 20 bed frame may serve for holding the pillows, or garments, and the folding legs 11 are received within this space. When the bed is in its lowermost position, or the position for use, the screen members are swung on their 25 hinges 18 and 19 to the position shown in Fig. 3, the lower ends of the screen members adjacent their swinging edges being cut away, in order to facilitate the swinging of the bed frame on its pivots 5.

30 The sides of the bed are preferably screened by screen sections 20 and 21 arranged on opposite sides of the bed. These sections are preferably connected to the sections 17 by hinges 22 which have three 35 leaves and are arranged in opposite pairs to permit the sections 20 and 21 to be swung in either direction and also to be folded into parallel relation with the sections 17, as shown in Fig. 3, so that the bed frame may 40 be swung toward and from an upright position. The lower swinging corners of the screen sections 20 and 21 are preferably cut away as at 23 to facilitate this swinging of the bed frame. It is apparent that the axes 45 of the screen sections 20 and 21 are at slight angles to the side pieces 4 of the bed frame in order that the screen sections will lie in vertical positions when the bed is swung to an upright position at a slight angle to the 50 vertical.

In the embodiment of the invention shown in Fig. 9, the parts are the same as those shown in Figs. 1 to 5, except that the sections 17^a are shorter than the sections 20 55 and 21, and the space below the sections 17^a is closed by a section 24 which is secured to the uprights 3 of the standard. With this arrangement no portion of the bed frame is visible, as is the case with the embodiment 60 shown in Figs. 1 to 5, due to the cutting away of the swinging corners of the sections 17.

In the embodiment shown in Figs. 6, 7 and 8, the parts are the same, except that 65 the bed frame and mattress are wider and

one of the sections 17, instead of having a section 21 hinged directly thereto has a strip 25 hinged to it at 27 by three-leaf hinges arranged in pairs to permit the strip to swing in either direction and to this strip 25 a side 70 panel or section 21 is connected by three-leaf hinges 28 arranged in pairs so as to permit the side piece 21 to fold in parallel relation to the section 17 in the manner shown in Fig. 7. Another difference in this 75 embodiment over that shown in Figs. 1 to 5, is the provision of an additional or intermediate section 29 between the sections 17. This intermediate section is connected with one of the sections 17 by three leaf hinges 80 arranged in pairs, and has both of its lower corners cut away at 31. Only one of these cut-away corners has a function, the other being provided merely for ornamental purposes. The section 29 is adapted to fold on 85 to the section 17 to which it is hinged, so that one of the cut-away corners 31 will lie over the cut-away corner 32 of said section 17 to facilitate the swinging of the bed frame on its pivot 5 when the screen sections are 90 folded into parallel relation, as shown in Fig. 7.

In all embodiments of the invention, when the bed is in position for use, the screen members or sections lie in parallel 95 relation at the sides of the bed below the bed frame, thus not interfering with the use of the bed. When it is desired to fold the bed, the bed is swung upwardly on its pivots 5 until its upper end passes beyond the vertical plane of the pivots 5 in which position the bed will be held by its own weight. The screen members are then manipulated so as to throw the side sections 21 to position to cover the side edges of the bed, while the 100 sections 17 for covering the bottom of the bed are then swung into alignment, thus further locking the bed frame in an upright position. Notwithstanding the fact that the side bars of the bed are not vertically arranged, the axes of the screen sections are so arranged, due to the angular relation between said axes and the side pieces of the bed frame, that free swinging movements of the screen sections are secured. The form 110 of screen herein shown makes unnecessary the provision of a cabinet in which the bed frame is enclosed, and at the same time an article of furniture is provided which is inconspicuous and also inexpensive to manufacture. 115

What I claim as my invention and desire to secure by Letters Patent is:—

1. In a bed, a support, a bed frame hinged to the support to swing to an upright position, and two screen members hinged to opposite sides of the frame to assume positions below the mattress when the bed is in the position of use and positions to cover the side edges of the mattress when the bed is 120 125 130

in an upright position, the lower corners of the screen members being cut away to permit the swinging of the bed frame on its support.

- 5 2. In a bed, a support, a bed frame hinged to the support to swing to an upright position, supporting means for the foot end of the frame foldably connected to the latter, two screen members hinged to opposite sides 10 of the frame to assume pendent positions on opposite sides of the support and the foldable supporting means when the bed is in the position of use and to cover the under side of the bed when the latter is in 15 an upright position, the lower corners of the screen members being cut away to permit the swinging of the bed frame on the support, and means flexibly connected to the screen members for covering the sides of 20 the bed when the latter is in an upright position.

3. In a bed, a support, a bed frame hinged to the support to swing to an upright position, supporting means for the foot end of the frame foldably connected to the latter, and two pairs of screen members hinged to 25 opposite sides of the bed frame, both members of each pair being arranged to assume pendent and parallel positions on opposite 30 sides of the support and foldable supporting means when the bed frame is in position for use, and one member of each pair being arranged so as to cover a side edge of the mattress while the other member of 35 each pair is arranged to cover partially the bottom of the bed frame when the bed frame is upright.

4. In a bed, a support, a frame pivoted to said support to swing to an upright position, a mattress, means for supporting the mattress on the frame when the latter is 40 swung to an upright position on the support, comprising cables extending along the sides of the mattress and secured thereto and to 45 the end of the frame which is uppermost when the latter is swung upwardly, and a stiffening strip arranged at the lower end of the mattress and having the cables engaging therewith.

- 50 5. In a bed, a support, a bed frame hinged to the support to swing to an upright position slightly beyond the vertical position, and two screen members hinged at opposite sides of the bed frame about axes at such 55 angles to the sides of the bed frame that said axes will be vertical when the bed frame is upright and the screen member can assume position below the bed frame when the bed is in position of use, and positions to 60 cover the sides of the bed frame when the bed is in an upright position.

6. In a bed, a support, a bed frame hinged to the support to swing to an upright position beyond the vertical, and screen members 65 for covering the bottom of the bed

frame hinged to the bed frame about axes at slight angles to the sides of the bed frame so that said axes will be vertical when the bed frame is upright.

7. In a bed, a support, a bed frame hinged 70 to the support to swing to an upright position slightly beyond the vertical, and a mattress supporting fabric supported on said bed frame at such an angle to the longitudinal axes of the side pieces of the bed 75 frame that the mattress will rest against the fabric when the bed frame is swung upright.

8. The combination in a bed, with a support and a bed frame comprising side pieces, 80 cross pieces connecting the side pieces at opposite ends of the latter, the cross piece at the head end of the bed being spaced from the side pieces at a greater distance than the one at the foot end of the bed, and 85 a mattress supporting fabric connecting said cross pieces, of means for pivotally supporting the bed frame on the support to permit said frame to swing to an upright position with its sides slightly beyond the 90 vertical, and foldable supporting means for the foot end of the bed frame arranged to hold the side pieces at a slight angle to the horizontal when the bed frame is lowered, the mattress supporting fabric being at such 95 an angle to the side pieces as to occupy a horizontal position when the bed frame is lowered and a substantially vertical position when the bed frame is upright.

9. In a bed, a support, a bed frame hinged 100 to the support to swing to an upright position, two screen members hinged at opposite sides of the frame beyond the outer sides of the supports to assume pendent positions when the bed is in position for use 105 and to cover the under side of the bed frame as well as the upper portions of the support when the bed frame is in an upright position, and means carried by the screen members for covering the sides of the bed when 110 the latter is in upright position.

10. In a bed, a support, a bed frame hinged to the support to swing to an upright position, two screen members hinged to opposite sides of the frame to assume pendent 115 positions when the bed is in position for use, a third screen member hinged to the swinging edge of one of the aforesaid screen members, a strip hinged to the swinging edge of said screen member to which the third 120 screen member is hinged, and still another screen member hinged to the strip to cover a side of the bed frame.

11. In a bed, the combination with a support, and a bed frame pivoted to the support and embodying two side pieces, cross bars connecting the side pieces and a fabric connecting the cross bars and lying to one side of the side pieces; of screen members 125 pivotally mounted on the side pieces below 130

the fabric and arranged to hang in a pend-
5 ent condition when the bed is in position for
use and to cover the bottom of the bed when
the bed frame is swung to an upright position,
the fabric and screens lying parallel
when the bed is lowered and at an angle
relatively to the side pieces.

12. In a bed, the combination with a sup-
port and a bed frame pivotally mounted on
10 the support and embodying two side pieces,
cross pieces connecting the side pieces and
a fabric connecting the cross pieces, of sup-

porting means foldably connected to the
foot end of the bed frame, two hinged side
screen members supported from the side 15
pieces below the fabric to depend on oppo-
site sides of the support and the foldable
supporting means when the bed frame is
lowered, and bottom screen members sup-
ported from the side pieces to depend on 20
opposite sides of the support and the fold-
able supporting means when the bed frame
is lowered.

GEORGE R. McALLASTER.
